Inventor
E. A. Cooper

UNITED STATES PATENT OFFICE

ETHEL A. COOPER, OF KANSAS CITY, MISSOURI

ATHLETIC KNEE SHIELD FOR THE PROTECTION OF MEN'S TROUSERS

Application filed November 18, 1927. Serial No. 234,281.

This invention relates to a knee shield and has for its principal object to provide a simple and efficient means for protecting outer garments such as trousers from direct contact with the knees and therefore from the effect of perspiration.

Another object of the invention lies in the provision of a knee shield which is constructed in a manner to maintain the same in proper position when the wearer is either in a sitting or a standing position.

With these and other objects in view which will more fully appear, the nature of the invention will be more clearly understood by following the description, the appended claim, and the several views illustrated in the accompanying drawing.

In the accompanying drawings:

Fig. 1 is a perspective view showing the application of my invention,

Fig. 2 is an enlarged perspective view showing the knee shield forming the subject matter of my invention, and

Fig. 3 is an enlarged detailed sectional view showing the connection between the body portion of the knee shield or pad, the reinforcing strip, and the leg encircling band.

Like reference numerals designate corresponding parts throughout the several figures of the drawings.

Referring to the accompanying drawings, the invention comprises a knee shield or pad consisting of a rectangular shaped body portion 5 of elastic water proof material, upper and lower reinforcing strips 6 and 7 which are respectively secured to the body portion along the upper and lower edges thereof by means of stitches, and side reinforcing strips 8 and 9 which are respectively attached to the body portion along the side edges thereof by stitches. In order to support the knee pad from the leg portions of underwear, as shown in Fig. 1, I have provided spaced supporting means 10 and 11 which are respectively connected to the upper edge portion of the pad through the medium of said stitches. In order to retain the pad in cooperative position relative to the knee, regardless of whether the wearer is standing or sitting, I have provided a plurality of spaced leg encircling

bands 12 having their ends respectively connected to the side reinforcing strips 8 and 9.

The bands 12 are continuous from one attaching end to the other, and are of such lengths to cooperate with the pad whereby a circular opening is provided of a size which will insure entire freedom at the lower extremity of the shield.

In view of the above it will be observed that I have provided a knee protector or shield which is composed of but few parts, and is constructed to maintain the supporting means and the leg encircling bands against tendency of becoming separated from the body portion and without injuring said body portion.

It is of course to be understood that the details of structure and arrangements of parts may be variously changed and modified without departing from the spirit and scope of my invention.

I claim:

A knee protector comprising a substantially rectangular body portion formed of elastic water-proof material, reinforcing strips stitched to the body along the upper, lower and side edges thereof, spaced supporting means for the protector and attached to the reinforcing strips at points along the upper portion of the protector by the stitches of the said strips, and a plurality of spaced leg encircling bands having their ends attached to the side reinforcing strips, with some of said bands at the ends of the protector and others between the ends.

ETHEL A. COOPER.
